UNITED STATES PATENT OFFICE.

WILLIAM E. ANDRÉE, OF CHICAGO, ILLINOIS, ASSIGNOR TO THE AMERICAN LAUNDRY MACHINERY COMPANY, OF CINCINNATI, OHIO, A CORPORATION OF OHIO.

GARMENT-PRESS.

1,368,684.

Specification of Letters Patent. Patented Feb. 15, 1921.

Application filed June 7, 1916, Serial No. 102,298. Renewed July 1, 1920. Serial No. 393,454.

To all whom it may concern:

Be it known that I, WILLIAM E. ANDRÉE, citizen of the United States, residing at Chicago, in the county of Cook and State 5 of Illinois, have invented certain new and useful Improvements in Garment-Presses, of which the following is a specification.

This invention relates generally to garment presses and particularly to presses of 10 the type having power mechanism applied for exerting the pressure.

More specifically the invention relates to a garment press comprising a frame supporting a lower buck, a supporting lever for 15 an upper buck, treadle mechanism, connections between the treadle mechanism and the supporting lever for bringing the upper buck into pressing position and power mechanism preferably arranged in conjunction 20 with the supporting lever operating mechanism for exerting a final pressure upon the work.

The invention may be further briefly summarized as consisting in the construction 25 and combination of parts hereinafter described in the following drawings, description and claims.

Referring to the drawings Figure 1 is a right side elevation of the machine; Fig. 30 2 is a detail view in elevation showing treadle lock operating mechanism; Fig. 3 is a left side elevation; Fig. 4 is a left side elevation of the lower portion of the machine with parts broken away and in section to 35 clearly show the mechanism. This view is taken with the upper left hand portion of the frame as shown broken away and is substantially a view taken just inside of the motor and the gear case and substantially on 40 the line 4—4 of Fig. 5, it being impossible to take any uniform section which would give an intelligent illustration of the mechanism; Fig. 5 is a horizontal section upon the line 5—5 of Fig. 4; Fig. 6 is a front elevation of the machine; Fig. 7 is a detail view in section on the line 7—7 of Fig. 1 showing the steam and vacuum valve mechanism; Fig. 8 is a detailed view partly in section 45 and partly in elevation looking at the switch mechanism as viewed from the left side of the machine; Fig. 9 is view partly in section and partly in elevation viewing the switch

mechanism at 90° to Fig. 5; Fig. 10 is a detail sectional view of a portion of the switch; Fig. 11 is a plan view of a lever; and Fig. 55 12 is a cross section on the line 12—12 Fig. 4.

In the embodiment of the invention shown in the drawings the several parts of the mechanism will be described under their separate headings.

60

Main frame.

The main frame of the machine comprises a base 1 having an open and substantially square standard 2 projecting upward therefrom with a rearwardly and upwardly extending arm 3 having side webs 4 and 5 extending down to the base 1 which is extended well beyond the rear of the standard 2.

65

Lower buck.

70

Mounted upon the upper end of the standard 2 is a lower buck support 6 of substantially the form shown, but preferably having a hollow chamber 7 therein adapted to 75 receive steam in any suitable manner and to supply this steam through the ports 8 to the central opening 9 communicating by openings 10 with channels 11 and 12 arranged in the upper surface of the main body portion 13 of the lower buck. Secured to the upper surface of this main body portion 13 is a perforated plate 14 adapted to be arranged under suitable padding 15 secured in any preferred manner to the lower buck.

80

The passage of steam through the opening 9 into the channels 11 and 12 is controlled by a valve 16 mounted upon a stem 17 extending downward and provided with a head 18 receiving a nut 19 secured to a rod 20 passing through a tube 21 and a stuffing box at its lower end. The end of this rod is connected by a suitable connection to an actuating rod 24 in turn pivoted to a steam treadle 25 mounted in the standard.

85

The main body portion of this buck is also provided with a vacuum passage casting 26 having a port 27 therethrough adapted to be controlled by a valve 28 arranged under the plate 14 in a manner to permit the 100 exhaust of air from under this plate and through the perforations therein. This valve is provided with a stem 20 passing down through the exhaust pipe 30 to an L 31

having a side opening connected to an exhaust pipe 32 leading to any vacuum line. The stem passes through the L 31 and through a stuffing box structure 33 and is 5 provided with a suitable collar 34 adapted for engagement by suitable actuating mechanism to be described.

Upper buck.

10 Pivotedly mounted in the upwardly extending arm 3 is an upper buck supporting and actuating lever having a forwardly extending arm 35 carrying an upper buck structure 36 pivotally mounted upon the 15 arm, and a rearwardly extending arm structure 37 provided with a counter balance weight 38. This arm 37 is connected at 39 to a coiled spring 40 in turn connected to the base so that the normal tendency of this 20 lever is to raise the upper buck when released.

Closing treadle mechanism.

Extending through the webs 4 and 5 is a 25 closing treadle pivot 41 receiving between the webs a treadle boss 42 having a closing treadle 43 extending through the frame to the front and there provided with a foot plate 44. This treadle lever near the foot plate 44, as shown in the drawings, is provided with an upwardly extending ear 45 adapted to engage between the arms of the clevis 46 threaded onto a rod 47 in turn engaging a connection 48 pivotally connected to 30 a lever 49 pivotally mounted upon a pin 50 supported in cross struts 51 secured to the standard. This lever has spaced side portions 52 which receive the pin 50, and its outer parallel arm portions 54 are pierced 35 to receive a pin 55 to which links 56 are pivotally connected. These links engage on the outside of the clevis 57 forming a part of the toggle link 58 connected at its lower end to a pin 59 mounted in a final 40 pressure toggle member 60 in turn pivoted at a point removed from the pin 59 to another pin 61 arranged between the webs 4 and 5 at the rear end of the base as shown. Engaging between the arms of the clevis 57 is a connection 62 threaded onto the end 45 of a rod link 63 passing through a swivel member 64 mounted upon a shaft 65 supported in the upper buck supporting lever arm 37 as shown in Fig. 3. A coiled spring 50 66 is arranged between this swivel member 64 and a nut 67 arranged upon the rod 63.

The closing treadle mechanism just described is in the position shown in Figs. 1 and 3 when the upper buck is raised and in 55 order to lower this buck the operator depresses the treadle 43 causing the lever 49 to rock in a clock-wise direction as shown in Fig. 3 and thereby causing the links 56 to straighten the toggle comprising the toggle link 58 and the toggle rod 63 and its as-

sociated parts. This rocks the upper buck supporting lever in a clockwise direction as shown in this same figure and brings the upper buck down upon the work in an obvious manner, the pressure toggle mechanism comprising the lower toggle link 58 and the toggle link member 60 being in the position shown in Fig. 3.

Final pressure mechanism.

This mechanism is for the purpose of rocking the lower toggle link structure 60 from the position shown in Fig. 3 to that shown in Fig. 4 or in other words, it is for the purpose of straightening the toggle structure formed by the toggle link 58 and the toggle link member 60. The toggle link member comprises two side link portions, each having an opening 68 for the reception of the shaft 61 and an opening 69 for the reception of the shaft or pin 59. These side link portions are connected by a connecting web 70 so that they will operate in unison. Secured to one of these side link portions of this toggle link member, is an actuating arm 71 having a recess 72 therein for the reception of the end of an operating arm 73 held in this recess by a suitable bolt 74. The end of this operating arm is provided with a longitudinally disposed slot portion 75 merging into an arc-shaped slot portion 76, the complete slot made up of the portions 75 and 76 receiving a crank pin 77 secured to the side of a gear wheel 78 mounted upon a shaft 79 supported in suitable bearings in 100 the frame. Secured to the back of the gear 78 and preferably formed integral with it is a cam 80 shown in dotted lines in Figs. 1 and 4 and partly in full lines in Fig. 2 and this cam is in the relation with respect to the crank pin 77 as shown in Fig. 1, and its object will later appear.

From the description of the crank pin and the lever 73 and assuming that the gear 78 rotates in a counter-clockwise direction as 110 shown in Fig. 1 and that the parts are in the position shown in this figure, then assuming that the treadle mechanism has been operated to bring the upper buck down upon the lower buck so that the toggle mechanism assumes the position shown in Fig. 4 except that the toggle link member 60 is not in a straight line with respect to the link 58, then as the gear 78 rotates the crank pin 77 travels out in the slot portion 75 and rocks the lever 73 straightening the toggle link member 60, or in other words bringing it into the position shown in Fig. 4 when the crank pin will be in the position shown in Fig. 2. At this particular time the drive 120 is stopped in any suitable manner and preferably by the breaking of the circuit of the motor, whose switch mechanism and control are later described. When the circuit to the motor is again closed by the switch and 130

its controlling mechanism or when power is again transmitted to the gear 78 so that it rotates in the same direction the crank pin operates in the slot portion 76 until it causes

5 the lever 73 to be rocked until these parts assume the position shown in Fig. 1 again, when the toggle link member will be returned to its normal position or the position which it assumes when the press is open.

10

Treadle lock.

In order to hold the press closed when the treadle is depressed by the operator and during the time that the final pressure is being

15 exerted as just described and obviously to prevent the breaking of the toggle formed by the links 58 and the toggle rod 63, a suitable lock is provided for the treadle and it comprises a swinging arm 81 mounted upon

20 a pin 82 secured to the inside front portion of the standard 2 and extending down to a point where it may engage a friction roller 83 provided on the pin 45, arranged in the ear 45 of the treadle lever 43. The extreme

25 lower end of this swinging arm 81 is provided with an arc shaped face 84 for engagement with the roller and a rearwardly extending portion 85 which receives a pin 86 extending to one side of the swinging arm

30 as shown in Fig. 5 and receiving the end of a rod 87. A hub 88 is provided upon this rod forward of the pin 86 and a spring 89 is arranged to the rear of this pin and between it and the stop or collar 90 provided

35 on the rod. This rod 87 passes through the frame and is pivotally connected, as shown in Figs. 1 and 2, to the lower end of a lever 91 secured to a pin 92 mounted on the web 5. A spring 93 is arranged between the

40 standard and this lever, and this spring forces a flat portion 94 of the lever 91 against the cam 80, as in Fig. 2.

It will be seen that when these parts are in the position shown in Fig. 1, the swing-

45 ing arm is out of the path of the friction roller 83. When the treadle is depressed, however, and the upper buck is brought down upon the work and the motor is started through its controlling mechanism as will

50 appear, the rotation of the gear 78 in a clockwise direction, as shown in Fig. 1, will cause the lever 91 through the rod 87 to move the swinging arm into the position shown in Fig. 4, which is above the friction

55 roller 83 of the treadle lever thus preventing the upward movement of this treadle lever and hence holding the press closed. In the meantime, however, as described, the toggle link member is being brought into

60 straight line position and the pressure is being applied to the work. The swinging arm 81 remains in this position until the releasing mechanism to be described is set in motion when it is withdrawn and the

65 treadle released. This does not occur, how-

ever, until after the final pressure toggle link member 60 is returned to the position shown in Figs. 1 and 3 or normal position.

Switch mechanism and control therefor.

70

This mechanism is best shown in Figs. 8 and 9. Mounted upon a bracket 95 secured to the web 5 is a boss 96 forming a part of a base 97 of a switch casing which includes in addition to this member 97 a

75

back casing member 98 and a removable front casing or cover 99 held in place in any suitable manner. Slidably mounted in the boss 96 is a switch tube 100 preferably of

metal and having a lower keeper notch 101 and an upper keeper notch 102 in the periphery thereof, these notches being in longitudinal alignment with respect to the tube.

This tube is provided with a key way for receiving the key 103 engaging in a suitable

80

recess 104 and this key prevents this tube from turning. The lower end of the tube is counterbored to form a spring recess 105 for a purpose to be described. The upper

85

end of the tube is provided with a threaded extension 106 for a purpose to be described. Extending transversely through the boss is a keeper pin recess 107 receiving a keeper

90

pin 108 adapted to engage in one or the other of the two recesses 101 and 102 and

95

this pin is forced inwardly by a spring 109 which thrusts against the head of the keeper pin at one end and against a plug 110

threaded in the boss. Threaded onto the extension 106 is an insulating switch tube

100

111 having longitudinally disposed segments 112 sunk into the periphery of the tube at various points on its circumference there being three shown in Fig. 8 and each of

these segments is of a length such that it

105

will reach from the one contact to the other of each pair as will appear. The upper end of this insulating switch tube is provided

with a spring recess 113. Slidably mounted in this tube and the metal tube 100 is an

110

actuating rod 114 threaded at its upper end to receive a thrust nut 115 and a check nut 116. Between the thrust nut 115 and the

bottom of the spring recess 113 in the insulating switch tube 111 is a spring 117

115

normally tending to force the switch tube endwise with respect to the rod 114. Below the metal tube 100 the rod 114 is threaded and receives a lower thrust nut 118 and a

check nut 119 the thrust nut 118 engaging a

120

coil spring 120 arranged between it and the bottom of the recess 105 and this spring likewise tends to force the switch tube 111 and 100 in a direction contrary to that resulting from the action of the spring 117. The

125

nuts 115 and 118 are of a size such that they will engage the ends of the switch tube structure and cause a positive movement thereof as will appear.

The extreme lower end of the rod 114

130

is provided with an operating head 121 having an elongated transversely disposed slot 122 adapted to engage a crank 123 projecting from the side face of a crank disk 124 mounted upon the end of the shaft 79 outside of the web 4.

It will be seen from the foregoing construction that as the crank disk rotates the rod 114 will be moved downward against the pressure of the spring 117 until the thrust nut 115 engages the upper end of the tube 111 when the latter will be moved positively until the keeper pin 108 is moved out of the lower recess 101 when the spring 117 will have sufficient pressure to move the sleeve downward with a quick action until the pin 108 passes into the recess 102, the reverse operation taking place when the rod is raised.

20 Mounted in a boss 125 in the lower casing member 97 and in an upper boss 126 in the casing member 98 is a switch sleeve actuating rod 127 provided near the boss 126 with keeper recesses 128 and 129. These recesses 25 are engaged by a keeper pin 130 held in place by a spring 131 thrusting outward against a plug 132. The upper end of this rod is provided with a suitable head 133 held in any adjusted position by a set screw 30 134. This head 133 is adapted to be engaged by a trip 135 (Figs. 3 and 4) pivoted upon a trip arm 136 secured to a rock shaft 137 mounted in the frame web 4 and having on its inner end an actuating lever arm 35 138 arranged in the path of a lug 139 provided on the lever 49, the arrangement being such that when the lever is rocked into the position shown in Fig. 4 the arm 138 is engaged and the latch raises the head 133 40 and the rod 27 into the position shown in Fig. 4 or with the pin 130 in the recess or notch 128.

The trip 135 is pivoted upon a pin 140 in a manner such that it engages the arm 136 45 when the head 133 is engaged but when this arm 136 moves down to the position shown in Fig. 3 this strip may spring upward and permit the arm to pass the head 133. A spring 141 holds this trip in normal position 50 with respect to the arm 136.

The lower end of the rod 127 is provided with a clevis 142 engaging one arm of a bell crank lever 143 supported upon a pin 144 secured to the web 4. This bell crank lever 55 is actuated by the release treadle mechanism which will be described.

Secured to the rod 127 inside of the switch casing is a switch sleeve member 145 secured in any suitable manner to a switch sleeve 60 146 of any suitable insulating material. This sleeve surrounds the switch tube 111 as shown. The sleeve carries suitable contacts or brushes and these brushes are arranged in pairs vertically as shown and the number of pairs corresponds to the type of mo-

tor used, the idea being that each pair will close one circuit of the motor to be closed. Each of these brushes comprises a metal holder 147 threaded into the sleeve 146 and guiding a carbon or other brush 148 held in engagement with the tube 111 by a spring 149 which in turn is held in place by a cap 150 threaded onto an extension of the holder 147. This cap also serves as a binding screw for one of the leads.

75 The several parts of this mechanism are arranged in a manner such that the motor circuit is controlled in the proper manner and the complete operation will follow in connection with the complete operation of the machine, the description of the operation of this switch mechanism being deferred until after the releasing treadle mechanism, which has considerable to do with the operation of this device, has been described.

Releasing treadle mechanism.

80 Mounted in suitable bearings 151 in the frame near the base is a release treadle shaft 152 having secured thereto a release treadle 153 provided with a foot plate 154 on one side of the shaft and a rearwardly extending arm 155 on the opposite side of the shaft. A spring 153 normally tends to hold this release treadle up or in the position shown in the drawing. This arm 155 is provided with a laterally extending member 156 adapted to extend down and engage the floor and form a stop for the plate 154 and to also serve to engage underneath the main treadle lever 100 143 to cause it to positively return to normal position with the opening of the press. This release treadle lever 153 is also provided with an upwardly extending arm 157 for a purpose to be described. Secured to the shaft 152 outside of the bearing is an upwardly extending switch shifting arm 158 having a flat plate portion 159 with a laterally extending hook engaging lug 160 preferably formed integral with an outer guide member 161. The plate 159 is also provided with a pin 162 extending laterally in the same direction as the hook engaging lug 160. Coöperating with the plate portions 159 and 161 and with the hook engaging lug 160 is a hook 163 mounted upon a rod 164 extending to the rear through a suitable opening in the frame and passing through an opening in a pivoted member 165 pivotally mounted in one arm of the lever 143. On one side of this pivoted member 165 is a collar 166 secured to the rod 164 and on the opposite side there is a coil spring 167 arranged between the pivoted member and the adjusting nut 168.

105 110 115 120 125 It will be seen from the foregoing description that when the release treadle is depressed or moved in a clockwise direction as shown in Fig. 4 the hook 163 will then be engaged by the hook engaging lug 160 and 130

the lever 143 will be rocked in a counter-clockwise direction with the result that the rod 127 of the switch mechanism will be moved downward into the position shown in

- 5 Fig. 9. This operation performs certain functions relative to the switch mechanism and it is desirable that this operation should not be permitted to be brought about by the operator while the machine is being closed 10 and while pressure is being brought to bear upon the buck, and during these several operations the hook 163 is positively held out of the path of the hook engaging lug 160 by a pad 169 adjustably mounted in the end of 15 a hook raising lever 170 mounted in the frame. This lever is pivoted at 170' and extends to the rear of the standard 2 and is there provided with an upwardly extending arm 171 provided with a friction roller 172 20 adapted to engage the periphery of the cam 173 mounted on the shaft 79. This cam is of such a shape and it is so located, as shown in Fig. 4, that the roller rests in the low part of the cam when the press is closed thus 25 placing the hook 163 in the path of the hook engaging lug 160 so that the operator may depress the release treadle at any time and cause the operation of the switch mechanism, as will appear, to set the power operating mechanism in motion to release the 30 press. But as soon as the press is released which consumes substantially a half a revolution of the shaft 79 then the friction roller is engaged and the lever 170 raises the hook 35 out of the path of the hook engaging lug 160 thus preventing the release operation of the switch until after the press has been closed.

Power appliance and its transmission.

- 40 Mounted on a suitable bracket 174 secured to the base is a motor supporting plate 175 supporting a motor 176. The shaft of this motor enters a gear case 177 of any preferred type but capable of supporting a 45 worm 178 which meshes with a worm wheel 179 mounted upon a power shaft 180 supported in suitable bearings in the frame in a position such that a pinion 181 thereon may mesh with the gear 78.

50 *Air valve actuating connections.*

- Pivottally connected to the arm 157 integral with the release treadle is a link 182 in turn pivoted to a suction valve operating 55 lever 183 mounted upon a shaft 184 supported in suitable bearings 185 secured to the frame and having a forked arm 186 adapted to engage a spring 187 arranged below the collar 34 on the suction valve 60 stem 29.

When the release treadle is depressed for the releasing operation then the vacuum valve is open and the chamber under the perforated plate of the lower buck is connected to the exhaust and the steam is ex-

hausted from the surface of the lower buck and from the material operated upon.

Complete operation.

Assuming that the machine is open then 70 the several parts of the mechanism of the press itself are in the position shown in Figs. 1 and 3 and the switch mechanism is in the position in which it is shown in Figs. 8 and 9. When the operator closes the 75 press by depressing the main treadle the upper buck is brought into engagement with the lower buck and the lower part of the mechanism assumes the position shown in Figs. 4 and 5 as has been previously described, except that the toggle member 60 has not been straightened into the positions shown in these figures and the cam 173 is in a position such that the hook 163 is 80 elevated out of the path of the hook engaging lug 160. In bringing about this result, however, the lever 138 has been engaged and the trip 135, through its engagement with the head 134 has raised the rod 127 and consequently the switch sleeve 146 85 bringing the several pairs of contacts onto the segments 112 thus closing the circuits through the several connections necessary for the operation of the motor. The motor is then set in motion causing the gear 78 90 to rotate in a clockwise direction as shown in Fig. 1 and to engage the lever 91 and move the swinging arm 81 out over the roller 83, thus preventing the release of the main treadle lever 43. Just as the shaft 100 79 is completing its half rotation the roller 172 is released from the high part of the cam and is dropped and therefore permits the hook 163 to drop onto the hook engaging lug 160 or into the position shown in 105 Fig. 3. During this operation, however, the crank disk 124 is rotated from the full line position shown in Fig. 8 toward the dotted line position shown in this figure with the result that the thrust nut 115, 110 engages the switch tube structure 111 until it is released, when it will move down by the action of the spring 117 as described and the circuit or circuits, which are at that time closed through the switch mechanism, 115 will be broken.

When the press is to be released the operator depresses the releasing treadle causing the hook engaging lug 160 to engage the hook 163 which has been lowered as described, causing the rod 127 to be moved downward into the position shown in Fig. 9, it having been previously raised when the press was closed. This operation causes the several brushes carried by the sleeve 146 120 to move into engagement with the segments carried by the switch tube structure thus again closing the circuits of the motor and causing its operation, with the result that the cam 173 will again raise the hook 125 130

163 and the lever 91 will be returned by its spring 93 and the swinging arm 81 will move to the rear releasing the roller carried by the main treadle. When this release is brought about then the extension 156 carried by the release treadle engages the main treadle and causes the opening of the press. In the meantime, however, the toggle member 60 is moved from its straight line position to the rear or normal position and the crank pin 123 is moving upward and at the proper time causes the nut 118 to engage the switch tube structure and cause it to snap into the position shown in full lines in Figs. 8 and 9 when the circuit will be broken and the machine will be ready for another operation. As the press is being opened the downward movement of the treadle 153 through the parts connected to the member 157 actuates the vacuum valve 28 thereby causing the suction to draw the vapor from the material which has been treated upon the surface of the lower buck. This treadle may be actuated at any time while the press is open since the hook 163 is raised out of the path of the hook engaging lug and at any time during the closed or open position of the steam valve, may be operated to permit the passage of steam to the material on the lower buck.

The press is released from the final pressure by a quick action by reason of the fact that the crank pin 77 not only exerts a raising action upon the actuating arm 71 but a camming action is produced between the pin and the upper wall of the arc shaped slot portion 76 as will be readily seen from Fig. 2.

Having described my invention, I claim:

1. In a garment pressing machine the combination with co-acting pressing elements movable one in relation to the other, means for applying steam to the garment between said elements, and means for removing the steam only when the pressing elements are open.

2. In a garment pressing machine the combination with co-acting pressing elements movable one in relation to the other, means for applying steam to the garment between said elements, and means for withdrawing the steam only when the pressing elements are open.

3. In a garment pressing machine the

combination with co-acting pressing elements movable one in relation to the other, means for applying steam to the garment between said elements, and means operable at will for removing the steam only when the pressing elements are open.

4. In a garment pressing machine the combination with co-acting pressing elements movable one in relation to the other, means for applying steam to the garment between said elements, and means operative during only the opening movement of the press for removing the steam from the garment.

5. In a garment pressing machine the combination with co-acting pressing elements movable one in relation to the other, means for producing said movement, means for applying steam to the garment between said elements, and means rendered effective by said first named means for removing the steam only when the pressing elements are open.

6. In a garment pressing machine the combination with co-acting pressing elements movable one in relation to the other, means for producing said movement, means for applying steam to the garment between said elements, and means rendered effective by a part of said first named means for removing the steam only when the pressing elements are open.

7. In a garment pressing machine the combination with co-acting pressing elements movable one in relation to the other, means for producing said movement and locking said elements in closed position, means for releasing said elements, means for applying steam to the garment between said elements, and means rendered effective by one of said first-named means for removing the steam only when the pressing elements are open.

8. In a garment press, a frame, a hollow buck, a foraminous plate upon said buck, an air circulating conduit connected to the chamber in said buck, motor means, means for applying power therefrom for the pressing operation, releasing mechanism, and means actuated thereby for establishing communication between the air circulating conduit and the chamber beneath the foraminous plate of the buck.

In testimony whereof I affix my signature.

WILLIAM E. ANDREE.
